UNITED STATES PATENT OFFICE

GEORGE F. SCULL, OF NEW YORK, N. Y., ASSIGNOR TO ROBERT HOE, OF NEW YORK, N. Y.

INKING MECHANISM.

No. 814,086.

Specification of Letters Patent.

Patented March 6, 1906.

Application filed February 1, 1904. Serial No. 191,439.

To all whom it may concern:

Be it known that I, GEORGE F. SCULL, a citizen of the United States, residing at New York, county of Richmond, and State of New 5 York, have invented certain new and useful Improvements in Inking Mechanisms, fully described and represented in the following specification and the accompanying drawings, forming a part of the same.

10 This invention relates to certain improvements in inking mechanisms.

Inking mechanisms as now ordinarily constructed usually include a plurality of form-rollers and one or more distributing-rollers 15 coöperating therewith. When the press is stopped, or when for any reason it is desirable to change the color of the ink, it is necessary to wash the ink from the rollers, and in order to do this it is desirable that the mechanism 20 be arranged in such a way that the composition rollers may be readily accessible. It has been customary heretofore to mount the vibrating distributing-rollers in a movable frame, the frame being so constructed that when in operative position the distributors are in contact with the form-rollers, the frame being thrown up, carrying the distributors away from the form-rollers when it is desired to clean the rollers. In some constructions 25 the frame has been thrown upward by means of suitably-arranged springs, the frame being locked in its operative position against the tension of these springs. These springs are, however, necessarily powerful, and great exertion is required on the part of the pressman to force the frame down after the rollers have been cleaned to move the distributors into their operative position. Power-operated devices for lifting this frame 30 have also been devised; but they have been located above the frame, and because of this location they interfere with the operations of the pressman in running the machine. Mechanisms have also been devised for lifting this frame, which include gear-operated lifting-rods. These devices, while furnishing sufficient power for operating the frame, are objectionable because the pressure of the frame 35 and distributors is sufficient to cause the gearing, which is hand-operated, to run in a reverse direction from that in which it was turned to raise the frame whenever the pressman releases his hold on the frame, and for this reason it has been necessary to supply

devices of this character with independent locking-means, which devices were expensive and cumbersome. Furthermore, in inking mechanisms as usually constructed the vibrating distributors, which were mounted in the movable frame before referred to, have 55 been given a vibrating movement by means of a suitable lever, mounted on an operating-shaft, the ends of the lever engaging collars on the rolls. When the movable frame was lifted, the collars were disengaged from the 60 ends of the lever, which remained stationary because it was mounted on the shaft. It frequently happened, however, that in lifting the rolls the distributors would shift somewhat, so that the operating-collars on the 65 shafts of these distributors would not engage with the ends of the levers when the frame was lowered into its operative position, and in order to effect the engagement it was necessary for the pressman to shift the rollers 70 lengthwise, which operation consumed time. 75

The present invention has for one of its objects to produce an inking mechanism embodying a movable frame in which the distributors are mounted and to provide in connection therewith an improved means for lifting the frame, which means shall be simple and economical in construction and effective in operation and which shall not require the use of extraneous locking devices to hold the 80 frame in its lifted position.

A further object of the invention is to produce an improved inking mechanism in which the distributors are mounted in the movable frame and in which the means for effecting the vibration of the distributors is connected to its operating means by discon- 85 nectable devices, which will enable the frame to be lifted without disconnecting the vibrating means from the distributing-rolls. 90

With these and other objects in view the invention consists in certain constructions and in certain parts, improvements, and combinations, as will be hereinafter fully described and then specifically pointed out in 95 the claims hereunto appended.

Referring to the accompanying drawings, Figure 1 is a side elevation of so much of the inking mechanism of a printing-machine as is necessary to an understanding of the invention. Fig. 2 is a sectional plan view, the section being taken on the line 2 2 of Fig. 1. Fig. 3 is a section on the line 3 3 of Fig. 1, 100 105

Fig. 4 is a diagrammatic view illustrating the frame in its raised position. Fig. 5 is a section on the line 5 5 of Fig. 1. Figs. 6 and 7 are detail views illustrating the locking mechanism.

Referring to the drawings, which illustrate one embodiment of the invention, the mechanism which has been selected to illustrate the invention is the inking mechanism of a bed-and-cylinder printing-machine.

The frame of the machine, which may be of any suitable construction, is marked 1. The form-roller stand, which may be of any preferred type of construction, is marked 2, the stand being bolted to the frame, as is usual. The inking mechanism shown embodies four form-rollers 3, the journals of these rollers being supported in open bearings of ordinary type, these bearings being supported in sockets in the stand in the usual manner and being adjustable, as is usual in such constructions. The stand is provided with two pairs of upwardly-extending projections 4, one projection of each pair being located on opposite sides of the machine. Inasmuch, however, as the illustration of only one side of the machine is necessary for an understanding of the machine, only one of each of these pairs is illustrated.

The movable frame for carrying the distributing-rolls may be variously constructed and may be mounted in any suitable manner. In the preferred constructions and as illustrated it consists of a pair of curved arms 5, these arms being pivoted at 6 to suitable brackets 7, attached to the frame. Only one of the brackets and arms is, however, shown, for the reasons before stated. The distributing-rolls (marked 8) have their shafts 9 suitably journaled in the arms 5, and the arms themselves rest on the projections 4 of the ink-roller stand before referred to when the distributors are in operative position.

As is usual in the class of inking mechanisms which has been selected to illustrate the invention, the distributors will be driven positively and will drive the form-rollers by friction. The means for driving these distributors may be of any suitable character. As shown, the shafts 9 are provided with gears 10, which gears are in mesh with pinions 11, mounted on studs 12, extending inward from the ink-roller stand. These pinions are arranged to be engaged by a rack on the reciprocating bed, the rack and bed being illustrated in dotted lines in Fig. 3. This construction for driving the distributors is a usual one, and any other desired means may be substituted therefor. In the construction illustrated rider-rolls 13 are provided, which run on the distributors, these rolls being journaled in open bearings 14, carried on the movable frame.

In order to obtain ready access to the rollers for cleaning purposes, the pivoted frame

is swung upward, and devices are provided for this purpose. While these devices may be varied in their specific construction, they will include a lifting-lever and suitable operating devices, the lever being located beneath the frame. Furthermore, this lever will be preferably so arranged that when the frame is in its raised position the strains produced by the weight of the frame will be lengthwise of the lever and through its center of

movement, so that the lever is self-locking. In the construction shown the lifting-lever is marked 15. In the preferred construction two of these levers will be employed, one on each side of the machine, although under some circumstances a single lever might be depended upon, if desired.

In the construction illustrated the lever or levers 15 are mounted on a shaft 16, supported in suitable bearings in the frame of the machine, and the lever is provided with an antifriction cam-roll 17.

The operating means for the lever may be varied within wide limits, but in the preferred construction the shaft 16 will have attached thereto a segment-arm 18, the teeth 19 of which engage with a gear 20, mounted on the frame of the machine. In the preferred construction this gear will be hand-operated and is illustrated as provided

with a handle 21, by which it may be turned. Preferably, also, the frame will be provided with a cam-block 22, against which the antifriction-roll 17 bears. It will be understood that by this mechanism the frame carrying the distributors may be readily lifted—as shown, for instance, in Fig. 4—and owing to the relation of the parts the weight of the frame when the same is raised will not tend to rock the lever or levers 15 about their center, so that no extraneous locking means are necessary to hold the frame in its raised position.

Preferably, however, there will be provided a stop 23, which operates to prevent the segment-arm from being swung too far over, so as to cause the roller 17 to run off the block 22.

The distributing-rollers will preferably be arranged to be vibrated as is customary in inking mechanism constructions of the type selected to illustrate the invention, and this vibrating mechanism, while it may be varied widely in construction, will preferably include a vibrating lever 24. The connection between the vibrating lever and the distributors may be effected in any desired manner; but preferably each of the shafts 9 will be provided with a grooved collar 25, with which the ends of the lever engage, this being a well-known construction. The operating means for the lever may be of any desired or usual character. As shown, these means include a vertical shaft 26, stepped in a bearing 27, mounted on the frame, the shaft being further supported by a bearing 28, located on the ink-roller stand. Any suitable means may be

employed for moving the shaft to effect the operation of the vibrating lever. In the construction shown the shaft carries a segment 29, which is engaged by a segment 30, mounted on a lever 31, this lever being pivoted on a stud 32, which is in turn carried on a bracket 33, secured to the frame of the machine. The end of the lever 32 is provided with the usual antifriction-roll and engages a cam 34 on a cam-shaft 35.

As has been pointed out, in former constructions it has been customary to connect the vibrating lever directly to the shaft, so that when the distributor-roll-carrying frame 5 was raised the ends of the vibrating lever were disengaged from the collars on the shafts of the distributor-rolls. If the rolls became shifted, therefore, the collars would not engage their levers when the frame was moved into its operative position, and this required a shifting of the rollers by the pressman. In accordance with the present invention the connection between the vibrating lever and its operating means is a disconnectible one, so 25 that the lever will always remain engaged with the collars or other means by which it vibrates the distributors.

The disconnectible connection between the lever and its operating means may be 30 widely varied in construction. As shown, however, the lever is mounted on a short shaft 36, said shaft serving as a power-transmitting section. This shaft is mounted in a bearing 37, secured to the movable distributor-roll frame. Suitable engaging devices will be provided between the power-shaft 26 and this transmitting-section 36. While these means may be of any suitable character, in the construction shown the shaft 26 is provided with a recessed block 38, and the power-transmitting section is provided on its lower end with a block 39, properly proportioned to engage the recess in the block 38.

It may happen that after the distributor-45 roller-carrying frame is raised the relative position of the power-transmitting section and the shaft 26 will be varied, so that the engaging devices referred to will not come into proper engagement. To insure the engagement of these devices, therefore, suitable tensioning means will be preferably provided. In the construction shown these tensioning devices include a spring 40, said spring being located between the bearing 37, before referred to, and the block 39, the tendency of this spring therefore being to cause the block 39 to engage the recess in the block 38 whenever the parts are in such relative position as to admit of this engagement.

60 While the weight of the frame and the parts which it carries might be sufficient to hold the frame in its operative position and to cause the engagement of the devices which secure the vibrating means and its operating means, there will preferably be employed

locking devices which will insure that the frame after being lowered is held in its proper operative position. These locking devices may be of any suitable character. In the construction illustrated, however, there is 70 provided a shaft 41, which extends across the machine from side to side, and preferably there will be provided at each end an eccentric-pin 42, each of these pins engaging an opening in a latch 43, these latches passing 75 through vertical slots 44 in the arms 49, constituting the frame. These latches are further preferably provided with slots 45, which engage pins 46, mounted in the arms. The lower hooked ends of these latches 43 engage 80 with keepers 47, which are formed on the inking-roller stand, before referred to. The shaft 41 is or may be provided with suitable operating means, such as a handle 48. It will be readily understood that by turning the shaft 85 41 by means of its handle the latches for engaging with their keepers, as indicated in Fig. 6, will be swung downward and outward by the movement of the eccentric-pins 42 into the position indicated in Fig. 7, so that the 90 frame may be readily raised. After the frame has been lowered the reverse movement of the shaft will swing the latches into the position shown in Fig. 6.

Changes and variations may be made in 95 the constructions shown by which this invention is carried into effect. The invention is not, therefore, to be limited to the specific construction herein shown and described.

What is claimed is—

1. In an inking mechanism, the combination with a pivoted frame carrying distributors, of a self-locking lifting-lever located beneath the frame, and means for operating the lever, substantially as described.

2. In an inking mechanism, the combination with a pivoted frame carrying distributors, of a self-locking lifting-lever located beneath the frame, a bearing-block, mounted on the frame against which the lever bears, 110 and means for operating the lever, substantially as described.

3. In an inking mechanism, the combination with a pivoted frame carrying distributors, of a lifting-lever located beneath the frame and bearing thereagainst near the pivot thereof, and means including a segment for operating the lever, substantially as described.

4. In an inking mechanism, the combination with a pivoted frame carrying distributors, of a lifting-lever located beneath the frame, a bearing-block for the lever mounted on the frame, and means including a segment and a gear for operating the lever, substantially as described.

5. In an inking mechanism, the combination with a pivoted frame carrying distributors, of a lifting-lever located beneath the frame, a bearing-block for the lever mounted

on the frame, and means including a segment and a hand-operated gear engaging with said segment for operating the lever, substantially as described.

5 6. In an inking mechanism, the combination with a movable frame, of distributor mounted thereon, a lever for vibrating the distributor, means for operating the lever, and a disconnectible connection between the 10 lever and its operating means, substantially as described.

7. In an inking mechanism, the combination with a movable frame, of distributor mounted thereon, a lever for vibrating the distributor, suitable means including a shaft for operating the lever, and a disconnectible connection between the lever and its operating means, substantially as described.

8. In an inking mechanism, the combination with a movable frame, of distributor mounted thereon, a lever for vibrating the distributor, an operating-shaft, and a tension-controlled operating connection between the shaft and the lever, substantially as de- 25 scribed.

9. In an inking mechanism, the combination with a movable frame, of distributor mounted thereon, a lever for vibrating the distributor, an operating-shaft, a spring-controlled operating connection between the shaft and the lever, and means for positively locking the connection to the shaft, substantially as described.

10. In an inking mechanism, the combination with a movable frame, of distributor mounted thereon, a lever for vibrating the distributor, a vertical operating-shaft, a power-transmitting section between the shaft and the lever, coöperating engaging devices 35 on the shaft and section, and means for insuring the engagement of these devices, substantially as described.

11. In an inking mechanism, the combination with a movable frame, of distributor mounted thereon, a lever for vibrating the distributor, a vertical operating-shaft, a power-transmitting section between the shaft and the lever, coöperating engaging devices 45 on the shaft and section, and a spring for insuring the engagement of these devices, substantially as described.

12. In an inking mechanism, the combination with a movable frame, of distributor mounted thereon, a lever for vibrating the distributor, an operating-shaft having a recessed locking-block thereon, a transmitting-shaft between the lever and the operating-shaft, said shaft having an engaging block 55 thereon coöperating with the recessed locking-block, and means for insuring the engagement of the two blocks, substantially as described.

13. In an inking mechanism, the combination with a movable frame, of distributor mounted thereon, a lever for vibrating the dis- 65

tributors, an operating-shaft having a recessed locking-block thereon, a transmitting-shaft between the lever and the operating-shaft, said shaft having an engaging block thereon coöperating with the recessed locking-block, and a spring for insuring the engagement of the two blocks, substantially as described. 70

14. In an inking mechanism, the combination with a movable frame, of distributor mounted thereon, means for locking the frame in operative position, a lever for vibrating the distributor, means for operating the lever, and a disconnectible connection between the lever and its operating means, sub- 75 stantially as described.

15. In an inking mechanism, the combination with a movable frame, of distributor mounted thereon, a lever for vibrating the distributor, an operating-shaft, a tension-controlled operating connection between the shaft and the lever, and means for locking the frame in its operative position, substan- 80 tially as described.

16. In an inking mechanism, the combination with a movable frame, of distributor mounted thereon, a lever for vibrating the distributor, a vertical operating-shaft, a power-transmitting section between the shaft and the lever, coöperating engaging devices 90 on the shaft and section, means for insuring the engagement of these devices, and means for locking the frame in its operative position, substantially as described.

17. In an inking mechanism, the combination with a movable frame, of distributor mounted thereon, a lever for vibrating the distributor, an operating-shaft having a recessed locking-block thereon, a transmitting-shaft between the lever and the operating-shaft, said shaft having an engaging block thereon coöperating with the recessed locking-block, means for insuring the engagement of the two blocks, and means for locking the frame in its operative position, sub- 100 stantially as described. 105

18. In an inking mechanism, the combination with a movable frame, of distributor mounted thereon, a lever for vibrating the distributor, an operating-shaft having a recessed locking-block thereon, a transmitting-shaft between the lever and the operating-shaft, said shaft having an engaging block thereon coöperating with the recessed locking-block, a spring for insuring the engagement of the two blocks, and means for locking the frame in its operative position, sub- 115 stantially as described. 120

19. In an inking mechanism, the combination with a pivoted frame, of distributor mounted thereon, a lever for vibrating the distributor, an operating-shaft, a tension-controlled disconnectible connection between the vibrating lever and its operating means, means for locking the frame in its op- 125 130

erative position, and means for lifting the frame, substantially as described.

20. In an inking mechanism, the combination with a pivoted frame, of distributers 5 mounted thereon, a lever for vibrating the distributers, an operating - shaft, a tension-controlled disconnectible connection between the vibrating lever and its operating means, means for locking the frame in its operative position, a lifting-lever pivoted beneath the frame, and means for operating the lever, substantially as described.

21. In an inking mechanism, the combination with a pivoted frame, of distributers 15 mounted thereon, a lever for vibrating the distributers, an operating - shaft, a tension-controlled disconnectible connection between the vibrating lever and its operating means, means for locking the frame in its operative position, a lifting-lever pivoted beneath the frame, and a gear and segment for

operating the lever, substantially as described.

22. In an inking mechanism, the combination with a pivoted frame, of distributers 25 mounted thereon, a lever for vibrating the distributers, a shaft, a spring - controlled power-transmitting section between the shaft and the lever, coöperating locking devices on the section and shaft, means for locking the 30 frame in its operative position, a lifting-lever pivoted beneath the frame and means including a segment and a hand-operated gear for operating the lever, substantially as described.

In testimony whereof I have hereunto set my hand in the presence of two subscribing witnesses.

GEORGE F. SCULL.
